UNITED STATES PATENT OFFICE

135,064

DESIGN FOR A TEXTILE FABRIC OR SIMILAR ARTICLE OF MANUFACTURE

Henry St. Clair Morford, Hempstead, N. Y., assignor to J. H. Thorp & Co., Inc., New York, N. Y., a corporation of New York

Application December 2, 1942, Serial No. 108,927

Term of patent 3½ years

To all whom it may concern:

Be it known that I, Henry St. Clair Morford, a citizen of the United States of America and resident of Hempstead, county of Nassau, and State of New York, have invented a new, original, and ornamental Design for a Textile Fabric or Similar Article of Manufacture, of which the following is a specification, reference being had to the accompanying drawing, forming a part thereof.

In the drawing,

Fig. 1 is a face view of a piece of textile fabric embodying my design, a complete unit of said design being embraced by the intersecting section lines, which unit is used as a repeat.

Fig. 2 is a sectional view taken on line 2—2 of Fig. 1.

I claim:

The ornamental design for a textile fabric or similar article of manufacture, as shown.

HENRY ST. CLAIR MORFORD.
